UNITED STATES PATENT OFFICE.

JAMES D. MAITLAND, OF DENVER, COLORADO, ASSIGNOR TO THE JACKSON FIRE PROOF PARTITION COMPANY, OF DENVER, COLORADO, A CORPORATION OF COLORADO.

FIREPROOF PARTITION.

1,146,586.

Specification of Letters Patent. Patented July 13, 1915.

Application filed April 11, 1914. Serial No. 831,150.

To all whom it may concern:

Be it known that I, JAMES D. MAITLAND, a citizen of the United States, residing in the city and county of Denver and State of Colorado, have invented certain new and useful Improvements in Fireproof Partitions; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to improvements in fire proof constructions as partitions, walls and ceilings and comprises a special construction of metal stud together with means for securing a suitable sheeting thereto. The stud and fastening means employed therewith are more especially intended and adapted for use with plaster boards of the various kinds utilized in the construction of partitions of the character indicated, though it is evident that my improvement may be combined with sheets of any other character.

The invention in its simple or fundamental form, consists of a metal stud having a part passing transversely between the adjacent edges of the sheeting, as plaster board sections, prongs or projections being punched out of the web or transverse portion of the stud for the purpose of engaging the plaster board sections on one side, while suitable means may be employed in connection with the stud for engaging and supporting the plaster board sections of the partition on the opposite side. Various devices may be used on the opposite side of the sheeting from the prongs or projections. The web or transverse part of the stud may have a slot inclined to the vertical direction of the stud, and adapted to receive keys which, as they are moved downwardly in the slots, act upon the plaster board or other sheeting sections by a wedging action. Other means, however, may be resorted to, as wedge-shaped keys or nails inserted in holes in which they fit, the holes being so arranged that as the keys are inserted and driven into place, they secure the plaster board sections by a wedging action. Again, the web of the stud may have prongs or projections punched out of the same and

spaced to engage the sheeting sections on both sides. It will be understood that these prongs or projections which are punched out of the stud are arranged in different vertical planes and are caused to extend in opposite directions from the web of the stud, whereby they embrace and support the adjacent sections of the partitions on both sides of the stud. Other forms of construction will be explained as this specification proceeds.

Having briefly outlined my improved construction, I will proceed to describe same in detail, reference being made to the accompanying drawing, in which is illustrated an embodiment thereof.

In this drawing,—Figure 1 is a fragmentary side elevation of a section of a plaster board partition constructed in accordance with my improvement. Fig. 2 is a vertical section taken through the same on the line 2—2, Fig. 1. Fig. 3 is a perspective view illustrating one form of my improved stud, the plaster board sections employed therewith being indicated by dotted lines. Fig. 4 is a section taken through the plaster board portion of the partition, viewed in the direction of the stud, which is of the construction shown in Fig. 3. Fig. 5 is a horizontal section taken on the line 5—5, Fig. 4, looking downwardly. Fig. 6 is a section similar to Fig. 5, but showing a modified form of fastening means for the plaster board sections on the opposite side from the prongs carried by the stud. Fig. 7 is an elevation of the form of construction shown in Fig. 6. This view will be obtained by looking in the direction of the arrow 7, Fig. 6. Fig. 8 is a perspective view of a flat stud showing prongs punched out of the same and extending in opposite directions from the body of the stud, the outer extremities of the prongs being hooked shaped. Fig. 9 is a view of still another form of stud, the same being adapted for use where double partitions are employed to form a hollow wall. Figs. 10, 11, 12 and 13 are sections similar to Fig. 6, but illustrating other forms of construction, these figures relating more particularly to the manner of securing the plaster board sections on the opposite side from the prongs or projections with which all forms of the stud are equipped. Fig. 14 is a perspective view of still another form of stud, in which projections punched out of the transverse portion or web of the

stud are employed for maintaining the sheeting sections in place on both sides. Fig. 15 is a horizontal section similar to Figs. 10 to 13, inclusive, showing still another form 5 or embodiment of the invention. Fig. 16 is a section illustrating my improvement applied at the corner of partitions where the two partition members are arranged at right angles to each other. Figs. 17 and 18 are 10 top plan views illustrating other forms or embodiments of the invention.

The same reference characters indicate the same parts in all the views.

Let the numeral 5 designate one form of 15 my improved metal stud, the same being channel shaped and having a web 6 adapted to pass transversely between the adjacent edges of the section 7 of the sheeting, while the flanges 8 give strength and rigidity to 20 the stud. Out of the web 6 of the stud are punched prongs or projections 9, which extend from the web of the stud in opposite directions, the said prongs being located at different elevations and lying between the 25 same vertical planes. These prongs are so arranged that they are adapted to closely engage the plaster board sections 7 on one side when the sections are brought into proper coöperative relation with the stud 30 for partition purposes. Suitably spaced transversely from the prongs 9 is a slot 10 also formed in the web or transverse part 6 of the stud, and so arranged that when a key, as a flat piece of metal 12 is inserted 35 in the slot and moved downwardly, it will engage the plaster board sections 7 on the opposite sides from the prongs or projections 9, by a wedging action. In this case, the upper extremity of the inclined slot is 40 farthest outwardly from the partition sections, and the slot extends inwardly toward the plane of the adjacent surfaces of these sections, the length of the slot being such as to permit the desired range of adjustment 45 of the key for securing purposes.

It is evident that instead of integral prongs 9 punched out of the web of the stud as illustrated in this and other views showing different forms of construction, 50 separate prongs or projections, as nails, might be driven into openings formed in the web of the stud and caused to project therefrom in the same manner and adapted to perform the same function as the integral prongs. The prong form is, however, preferable, inasmuch as this construction is cheaper and is believed to be better for the purpose intended.

From what has just been explained, the 60 manner of constructing a partition of the character indicated where the form of stud just explained is employed, will be readily understood. The studs are arranged at suitable intervals depending on the width of the partition sections 7, the studs in the ordi-

nary vertical partitions being vertically arranged endwise between upper and lower sills or supports 13 and 14. Assuming that the prongs 9 are employed, the partition sections are placed edgewise against the webs 6 70 of the studs and so that the said prongs engage the adjacent sections on one side. The keys 12 are then inserted in the slots 10 and forced downwardly against the partition sections on the opposite side, whereby the 75 sections are held securely in place. As illustrated in the drawing, the top and bottom supports 13 and 14 are mortised to receive the opposite extremities of the studs. It is evident, however, that the studs may be secured in any other suitable manner.

In the form of construction shown in Figs. 6 and 7, a U-shaped clip 15 is employed instead of the slot and key disclosed in Figs. 1 to 5, inclusive. This U-shaped 85 clip is closed at one end as shown at 16, where it passes outside of one of the flanges 8 of the channel bar stud 5. From the extremities of the part 16, the parallel arms 17 of the clip pass transversely between the 90 partition sections 7, their free extremities being bent outwardly to engage said sections on the opposite side from the prongs 9.

In the form of construction shown in Fig. 8, the stud is flat or lies in a single plane. 95 This form of stud may be designated by the numeral 19. Prongs 19 are punched out of the stud and extend in opposite directions therefrom, whereby they are adapted to engage the partition sections 7 in the same 100 manner as the other forms of prongs, except that the prongs 19 are offset or hooked shaped at their outer extremities as shown at 20, whereby they may be caused to slightly indent the adjacent surfaces of the 105 partition sections, (see Fig. 10).

In Fig. 9 a stud is disclosed consisting of a flat bar of metal 21, having prongs 9 punched therefrom in opposite directions, there being two sets of these prongs which 110 are suitably spaced to support partition sections on the inside where a hollow wall is to be constructed. In this case, the transverse space between the two sets of prongs 19 is, the width of the space between the two 115 members constituting the double wall. The opposite side edges of this stud are provided with slots 22, which are inclined downwardly and inwardly in the direction of the sheeting. The upper extremities of these 120 slots are open to receive keys adapted to engage the sheeting by a wedging action when the keys are moved downwardly in the slots.

In the form of construction shown in Fig. 10, the form of stud illustrated in Fig. 8 is 125 employed, but the partition sections 7 are held in place on the side opposite from the prongs 19, by T-shaped spring clips 23, which as shown, are formed from an integral piece of spring metal having a part 24 130

extending parallel with the adjacent surface of the sheeting. At the outer ends of the part 24, the metal is bent on itself and carried inwardly toward the stud, as shown at 25, where it is again bent as shown at 26 and terminates in spring arms 27 adapted to pass between the adjacent edges of the plaster board sections, and tightly engage the flat bar stud on opposite sides. This 10 clip is forced upon the stud and into co-operative relation with the plaster board sections in a manner that will be readily understood when it is explained that the parts 27 are under tension, their free extremities being curved slightly away from each other to facilitate the application of the clip to the outer edge of the stud. Then as the clip is forced inwardly toward the partition, the spring arms will be separated 20 and placed under tension to tightly embrace the body of the stud, while the exterior portion of the clip will engage the plaster board section 7 on the opposite side from the prongs or projections 19.

25 The form of construction shown in Fig. 11 is substantially the same as that shown in Figs. 1 to 5, inclusive, except that a wedge shaped nail or key 28 is inserted in an opening formed in the web 6 of the channel bar stud 5, to receive the key or wedge shaped nail which is driven thereinto, whereby it is caused to tightly engage the sections 7 of the plaster board on opposite sides of the stud.

30 35 In the form of construction shown in Fig. 12, a T-shaped stud is employed, the prongs 9 being punched out of the web 29 thereof to engage the plaster board sections on one side, while the flanges 30 of the head of the 40 stud engage the said sections on the opposite side.

45 In the construction shown in Fig. 13, the form of stud illustrated in Fig. 14 is employed, consisting of a channel bar 31 having two sets of spaced projections, one set being designated 32 and the other set being designated 33. The partition sections 7 are inserted between these two sets of projections, which are suitably spaced for the 50 purpose.

55 In the form of construction shown in Fig. 15, a flat stud 34 is employed, having prongs or projections 35 extending therefrom on opposite sides and each provided with a series of teeth 36, adapted to indent the adjacent surfaces of the plaster board sections; while on the opposite side, a key 12 is employed.

60 65 In the form of construction shown in Fig. 16, the plaster board sections 7 are arranged at right angles to each other and the channel stud 37 is placed at the corner, the web 38 passing diagonally between the beveled adjacent edges of the partitions. Prongs 39 are punched out of the web and bent in di-

rections parallel with the right angularly arranged partition sections, these prongs being connected with the sections by wire loops, whose arms are passed through the partition sections and secured by twisting 70 their extremities, as shown at 40.

In the form shown in Fig. 17, a flat bar stud 41 is employed and prongs 42 are punched therefrom in such a manner that the prongs must be bent outwardly in order 75 to engage the adjacent surfaces of the partition sections 7. In bending them out, they are also given a half twist as shown at 43, whereby their edges engage the plaster board sections. On the opposite side the 80 form of key 12 is disclosed.

In Fig. 18, the construction is substantially the same except that the prongs are given a quarter twist as shown at 44, instead of a half twist, as disclosed in Fig. 17. 85 Hence, in Fig. 18, the flat sides of the prongs or projections are in engagement with the adjacent surfaces of the plaster board sections.

90 From the foregoing description, the manner of installing partitions embodying my invention will be readily understood and need not be described in detail. It is evident that the metal stud carrying or provided with prongs extending from the part 95 thereof occupying a transverse position with reference to the sheeting, regardless of the form of the stud in other respects, is the primary or fundamental idea of the invention, since various other means or devices 100 may be employed for securing the sheeting on the side opposite that engaged by the said prongs; while it is preferred to employ means applied to the stud in such a way as to produce a wedging action as by a key 105 passed through a slot properly inclined for the purpose, other forms of construction may be employed as indicated in the drawings and still others will readily occur. My only object is to indicate in a general way a 110 few of the possible constructions that may be employed without departing from the invention.

115 Attention is called to the fact that while the term "partitions" has been more particularly referred to as the structure with which my improvement is adapted for use, it must be understood that this term is of sufficient scope to cover walls of all character, as ceilings, floors and outside walls, as 120 well as walls of the character usually termed partitions. Furthermore, while in the construction as disclosed, the prongs or projections with which the studs are equipped are arranged in longitudinal alinement, 125 which of course, is the preferred form and in fact, the form which will in most cases be employed, it must be understood that a construction is clearly within the scope of the invention in which these prongs or pro- 130

jections are staggered, or out of longitudinal alinement. In some cases, the peculiar construction of the wall or partition may require such staggered arrangement of the 5 prongs.

Having thus described my invention, what I claim is,—

1. A metal stud for sectional partitions whose web or body plate extends trans- 10 versely of the partition and lies between and spaces and substantially engages the adjacent edges of the sections forming the joint, the said web or body plate being equipped intermediate its longitudinal 15 edges with projections extending in opposite directions and longitudinally alined and spaced and adapted to engage the flat surfaces of the sections on one side, and means mounted on the body plate beyond the said 20 projections for engaging the partition sections on the opposite surface from that engaged by the said projections.

2. A metal stud of the class described whose body plate extends transversely of the 25 partition and lies between and spaces and substantially engages the adjacent edges of the sections forming the joint, the said body plate being equipped with integral projections punched out of the said plate portion 30 of the stud intermediate its longitudinal edges and extending in opposite directions therefrom, said projections being longitudinally alined and spaced and adapted to engage the flat surfaces of the sections on one 35 side, and means mounted on the body plate beyond the said projections for engaging the partition sections on the opposite surfaces from that engaged by the said projections.

3. A metal stud for sectional partitions 40 comprising a channel bar whose web or body plate extends transversely of the partition and lies between and spaces and substantially engages the adjacent edges of the sections forming the joint, the said web or 45 body plate being equipped intermediate its longitudinal edges with projections extending from the web or body plate in opposite directions and adapted to engage the flat surfaces of the sections on one side, the said 50 projections being longitudinally alined and spaced, and means mounted on the web or body plate beyond the said projections for

engaging the partition sections on the opposite surface from that engaged by the said 55 projections.

4. A stud having two sets of projections transversely and longitudinally spaced, each set being also longitudinally alined and adapted to engage sheeting sections applied to their outer sides to form a hollow partition composed of two members, the web or body portion of the stud lying between and spacing the adjacent edges of the sections forming the joints of each of the said members, and means applied to the stud beyond the two members of the partition for 60 securing the sections of said members in place.

5. A stud having two sets of projections transversely and longitudinally spaced, the 70 individual projections of each set being also longitudinally alined and adapted to receive and engage partition sections to form a hollow partition composed of two parallel members, the web or body portion of the 75 stud lying between and spacing the adjacent edges of the partition sections forming the joints of both of said members, the stud projecting transversely exteriorly beyond the partition members, and having slots 80 formed therein and fastening keys inserted in the slots and engaging the flat surfaces of the partition members on the outside and in opposing relation to the said projections, substantially as described.

6. A stud having two sets of spaced projections extending from its web or body part, the latter extending transversely of the partition, said projections adapted to form a support on the inside for two partition members composed of said sections whose edges are arranged adjacent the opposite sides of the body of the stud which spaces the said edges which form the joints of the partition members, and means applied to the outer portions of the stud beyond the partition members for securing the 90 said members in place by a wedging action.

In testimony whereof I affix my signature in presence of two witnesses.

JAMES D. MAITLAND.
